CLAIM

I claim the ornamental design for a table, as shown and described.

DESCRIPTION

The patent or application file contains at least one drawing executed in color. Copies of this patent or patent application publication with color drawings will be provided by the Office upon request and payment of the necessary fee.

FIG. 1 is a top perspective view for a table showing my new design.

FIG. 2 is a bottom perspective view thereof.

FIG. 3 is a side elevation view thereof.

FIG. 4 is a top plan view; and,

FIG. 5 is a bottom view thereof.

The broken lines shown in the drawings illustrate portions of the table that form no part of the claimed design.

**1 Claim, 5 Drawing Sheets
(2 of 5 Drawing Sheet(s) Filed in Color)**

FIG. 1

FIG. 2

FIG. 3

FIG. 4

FIG. 5
